CLAIM

The ornamental design for a waste bin with user control buttons, as shown and described.

DESCRIPTION

FIG. 1 is a front left perspective view of a waste bin with user control buttons of the invention;

FIG. 2 is a top perspective view of a waste bin with user control buttons of the invention; and,

FIG. 3 is an enlarged view of the user control buttons shown in FIG. 2.

The dash-dash broken lines illustrate portions of the article. The dot-dash broken lines indicate the location and boundary of the enlarged partial view. None of the broken lines form part of the claimed design.
